AUXILIARY COMMUTATING FIELD

Maurice J. Pasculle, Pittsburgh, Pa., assignor to
Westinghouse Electric Corporation, East Pittsburgh, Pa., a corporation of Pennsylvania

Application June 14, 1952, Serial No. 293,637

2 Claims. (Cl. 318—350)

1

My invention relates to means for improving the commutation of direct-current dynamo-electric machines, and it is particularly applicable to variable-speed shunt-type motors, which are of such a size as to require variation of the commutating-pole excitation under different shunt-field excitations, in order to obtain good commutation.

In large variable-speed direct-current motors, in which a considerable speed-variation is obtained by adjustment of the shunt-field excitation, it has been known, for some time, that when the shunt-field excitation is increased, at some predetermined load such as full-load, certain increases must be made in the interpole-flux which is produced by the series commutating-pole winding. Otherwise, poor commutation results. The reason for this phenomenon is not altogether clear. It is supposed, in some vague way, that saturation must be at the bottom of the difficulty, and massive field-frames are usually provided in an effort to avoid such difficulties, but the difficulties persist, even though no trace of saturation can be directly discovered by experimental methods. Heretofore, therefore, it has been necessary to provide an adjustable-resistance shunt around the series commutating winding, in order to provide a properly adjusted commutating-pole field-strength. Such machines have to be individually tested in the factory, before being shipped or used, because the currents which are involved are large, commutation is difficult to achieve, and the conditions of individual motors are sufficiently different to require individual factory-adjustments on each motor.

An important object of my invention is to improve the commutation of an adjustable-field variable-speed direct-current motor, by using the shunt-field current or voltage to excite an auxiliary commutating-field winding.

Heretofore, the necessary individual adjustment has been commonly accomplished by means of a shunt, having the necessary variable resistance, connected across the terminals of the series commutating winding, and mechanically connected to the shunt-field rheostat. Sometimes as much as 100 amperes or more have had to be carried by these shunts, and the value of the shunt-resistance has been subject to considerable variation. Each motor has had to be shop-tested at some predetermined load, such as full-load, at several different values of the shunt-field excitation, in order to determine the proper value of the shunt-resistance at each of these excitations. Then a suitable shunt-varying rheostat had to be made

2

up, mechanically coupled to the shunt-field rheostat, so as to have the proper values at the various tested points. Hence, it has been difficult to stock a sufficient variety of shunts to serve the requirements of all motors which are being made at a particular factory. This has resulted in delays in the shipments of the motor, which have had to be tested after the motors were otherwise finished and ready for shipment, and then a wait has been involved, in all too many instances, while the factory had to send away for a special high-current shunt having particular exact values of resistance at the various points.

Furthermore, no-load sparking has been a problem on some of these motors and generators, generally as a result of spray-flux from the main pole-tip into the commutating zone, due to unexplainable variations in individual motors as they come through the factory. When this no-load sparking has occurred, considerable time and money have been spent on the test-floor, by minutely adjusting the brushes to their positions of best commutation, sometimes machining off the edges of the main pole-tips, and sometimes resorting to other expedients.

While the ideal interpole-flux at no load assumes that there will be no flux-fringing or spraying, and hence assumes a zero commutating flux under said no-load conditions, there is always a certain amount of flux-fringing, even though such flux-fringing only occasionally reaches such magnitudes as to cause commutator-sparking at no load. My invention provides a cumulatively acting auxiliary commutating winding, which is adjustably excited from the same current or voltage which is applied to the shunt-field winding. Since the shunt-field excitation is never zero, the excitation of my auxiliary commutating winding is never zero, thus producing an interpole-excitation in the direction which is necessary to reduce or prevent no-load sparking, while at the same time effecting the necessary adjustment of the interpole-flux under different shunt-field excitation-conditions.

An important object of my invention is therefore to provide an auxiliary commutating winding, drawing a current which is considerably smaller than that which flows through the main or series commutating winding, so that it is relatively easy and inexpensive to adjust the excitation of the auxiliary commutation winding, and so that other advantages may be obtained, as will be pointed out hereinafter. Auxiliary commutating windings have been known before, in other types of machines, and for other purposes,

and with other connections and adjustments, as shown for example in a Miner Patent 2,530,982, granted November 21, 1950, but my invention differs therefrom in the details of their use and application, as well as in the results which are accomplished.

In the case of variable-speed direct-current motors, the objects and accomplishments of my invention include also the achievement of a flatter speed-characteristic on overloads.

With the foregoing and other objects in view, my invention consists in the machines, combinations, systems, connections, parts, and methods of design and operation, as hereinafter described, and illustrated in the accompanying drawing, wherein:

Figure 1 is a diagrammatic view of circuits and apparatus, illustrating my invention in a preferred form of embodiment,

Figs. 2, 3 and 4 are similar views illustrating modified connections and applications of my invention, and

Fig. 5 is a fragmentary view illustrating the positioning of the windings on the field-frame of an illustrative motor or generator embodying my invention.

My invention, while possibly not altogether limited thereto, is particularly applicable to, or needed in, direct-current shunt-excited dynamo-electric machines, particularly motors, in sizes above a 28-inch armature-diameter, with pole-numbers ranging from 6 poles, with a 32-inch armature-diameter, up to 24 poles, with a 144-inch armature-diameter, or even larger machines, if they are built. My invention is particularly applicable to variable-speed motors, which require shunt-field excitations which are varied over a rather considerable range, for considerable speed-variation or control. At present, the largest commercial use of my invention is in the field of variable-speed motors, such as are used in steel-mills, and in many other industrial uses.

In Fig. 1, I have diagrammatically indicated my invention as applied to a motor which includes an armature M, a shunt-type field-winding 10 which may be either separately or self-excited, a series compensating winding 11, a series commutating winding 12, and an auxiliary commutating winding 13. The motor is essentially a shunt-motor, which either has no series field winding (as shown), or if a series field winding is used at all it will have only a small compounding-effect.

As shown in Fig. 5, the field-frame of the motor comprises a cylindrical yoke 14, having main poles 15 and commutating poles or interpoles 16 bolted thereto. In accordance with a known practice, the main poles have a pole-shank portion 20, which carries the shunt-field winding which is diagrammatically indicated at 10 in Fig. 5, and a pole-tip portion 21 having slots 22 for receiving the compensating winding 11. The interpole 16 carries both the main or series commutating winding 12 and the auxiliary commutating winding 13, both of which are diagrammatically indicated in Fig. 5. In accordance with a known practice, the rear end 26 of the interpole 16 is spaced from the yoke or frame-member 14 by means of a plurality of magnetizable shims 27, the number of which can be varied, for the purpose of adjusting the effective inter-polar airgap 28 between the face 29 of the interpole and the periphery of the armature or rotor-member M. It will be understood that the number of the rear-end shims 27 can be adjusted

by removing the bolts 30, and then reassembling the interpoles 16, with the desired number of shims back of them.

Referring again to Fig. 1, it will be seen that my shunt-field winding 10 is provided with field-winding terminals which are marked E- and E+. In most commercial applications of my invention, the shunt-field winding 10 will be separately excited, so that the field-winding terminals E- and E+ will be connected to a separate source of excitation, other than the voltage which appears across the terminals of the armature M, although my invention is also applicable to a self-excited machine, in which the field-winding terminals E- and E+ are connected across the supply-line (+) and (-), or across the terminals of the armature M, as indicated in Figs. 3 and 4. In either event, whether separately excited or self-excited, my shunt-field winding 10 is necessarily provided with a shunt-field excitation-circuit 31 which includes a shunt-field regulating-means 32, either manual or automatic, for varying the excitation of the shunt-field winding over a considerable range, this regulating-means being indicated in the form of a field-rheostat 32, which is intended to be representative of any field-varying means.

The main armature-circuit of the motor, as shown in Fig. 1, is connected across a suitable constant-voltage direct-current supply-line, represented by the terminals (+) and (-), such as a 600-volt direct-current line, for example. The series compensating winding 11 and the series commutating winding 12 are connected as a series-winding circuit-portion 11-12, which is in turn connected in series with the armature M, and all three serially connected parts are connected across the supply-line represented by the terminals (+) and (-).

When the shunt-field winding 10 is separately excited, its excitation-terminals E+ and E- are commonly connected to a constant-voltage supply-line having a smaller voltage, for example 200 volts, although of course I am not limited to these details, in the application of my invention.

In accordance with my present invention, I provide a commutation-controlling means, for variably exciting the auxiliary commutating winding 13. The auxiliary commutating winding 13 is made of much smaller wires or conductors, than the series commutating winding 12, and the auxiliary commutating winding 13 is adapted to carry much smaller currents than the series commutating winding 12. Also, in accordance with my invention, the auxiliary commutating winding 13 is cumulative with respect to the main or series commutating winding 12.

It is an important feature of one aspect of my invention, that some means must be provided for varying or controlling or regulating or adjusting the exciting-current in the auxiliary commutating winding 13, either for making a preliminary general adjustment, suited to the idiosyncrasies or individual requirements of an individual machine, or for adjusting the excitation automatically in response to the magnitude of the shunt-field adjustments of the machine.

Thus, in Figs. 1, 2, 3, and 4, I have shown excitation-means or connections, for causing the excitation of the auxiliary commutating winding 13 to vary in response to variations in the excitation of the shunt-field winding 10. In many instances, the excitation of the shunt-field winding 10 is varied, by manual adjustments of the field-rheostat 32, so as to vary the speed of the

motor. In Figs. 1 and 3, the auxiliary commutating winding 13 is connected in series with the shunt-field winding 10, and said auxiliary commutating winding 13 is shunted by a variable-resistance shunt 33, which serves as an adjustment-means whereby to adjust the ratio of responsiveness of the excitation of the auxiliary commutating winding 13 in dependence upon the excitation of the shunt-field winding 10.

In Figs. 2 and 4, a variable rheostat 34 is connected in series with the auxiliary commutating winding 13, and said rheostat and auxiliary commutating winding are connected in a shunt circuit across the terminals of the shunt-field winding 10, so as to be responsive to the effective voltage which is applied to the shunt-field winding 10. Thus, the variable rheostat 34 of Fig. 2 or 4 serves the same general purpose as the adjustable-resistance shunt 33 of Fig. 1 or 3.

While the essential connections and physical structures have thus far been described, it is important to note the relative degrees or magnitudes of the total effective interpolar excitation which is provided by the combined operation of both of the commutating windings 12 and 13. It is necessary, also, to bear in mind the essential object of my invention, which is to provide the interpolar excitation-control or adjustment which is necessary to give each individual machine satisfactory commutation, and to do this without requiring the heavy-current shunting-resistors which have been previously used, in this type of machine, for adjusting the excitation of the main series commutating winding 12.

The ideal interpolar or commutating excitation-curve for a direct-current machine, plotting the total effective ampere-turns on the interpole 16 (in excess of the excitation necessary for compensation), against the load or armature-current, is a straight line, starting at zero ampere-turns at no-load, and running up to a certain definite magnitude, or narrow range of magnitudes, at a predetermined load which is at least as large as full load, and sometimes somewhat higher than full load. In other words, the commutating conditions must be right, not only at no load, but also at this predetermined load-value which is full-load or higher than full-load. At extreme overloads, such as double full load, or two and three-quarters times full load, interpole-saturation definitely comes into the picture, and the interpolar excitation need not always be ideal for such conditions.

The motors to which my invention is applied are big machines, which are individually hand-adjusted, on the test-floor, to have the proper operating-characteristics, before said machines are sold or put into use. The main or series commutating winding 12 is made of heavy strap-conductors, frequently having only one turn for each interpole, and the number of turns (and hence the ampere-turns), of this main series commutating winding 12, cannot readily be adjusted, except by means of the previously used commutating-winding shunt, or a cumulative auxiliary commutating winding 13, as in my present invention. It is essential that the total interpolar flux shall approximate an ideal value at the previously mentioned predetermined load-condition which is at least as large as full load, and if the machine is an adjustable-field variable-speed motor, involving the adjustment of the shunt-field current over a considerable range, say from full-field to a value which is from 15 to 25% of the full-field current, the ideal value of said total interpolar

flux is different for different shunt-field excitations.

The adjustment of the interpolar flux is made initially, once and for all, before the motor is shipped, by means of factory-tests at the previously mentioned load-condition which is at least as large as full load. While this load is being maintained, the shunt-field rheostat 32 is varied from its maximum to its minimum position, and the optimum interpole-flux is determined at both maximum and minimum shunt-field rheostat-settings. This gives the number of ampere-turns difference, between the excitation of the auxiliary commutating winding 13 at full field and at short field of the motor. At the same time, the optimum value of the interpolar airgap 28 is determined.

A check is also made at no load, leaving the shunt-field rheostat 32 in its maximum-field position, to see whether the excitation of the auxiliary cumulative interpole-winding 13 is too great to be within the tolerable interpole-excitation range at which sparkless commutation is obtained at no load. Since there is always some fringing of the flux from the main-pole tips 21 to the commutating zone, the cumulative interpolar flux of the auxiliary winding 13 is in the proper direction for overcoming the effects of this flux fringing. Usually the optimum amount of auxiliary-winding interpolar-excitation which is determined on full-load tests is quite acceptable at no load. In some rare instances, this interpolar-excitation may be too much at no load, in which case it may be necessary to reduce the auxiliary-winding excitation somewhat, so as to obtain not quite the best commutation at full load, but still giving preference to the commutation-conditions at full load, as distinguished from the commutation-conditions at no load.

It will be understood of course, that once the excitation of my auxiliary commutating winding 13 has been adjusted on the test-floor, by the proper adjustment or choice of the value of the resistance 33 or 34, as the case may be, then that resistance-value will thereafter remain unchanged, throughout the subsequent use of the motor.

The motor is then taken off of test, and the interpolar retaining-bolts 30 are removed, so that the number of shims 27 can be varied initially, once and for all, before the motor is shipped, as may be needed, to make the interpolar airgap 28 have the optimum value which was determined on test.

The interpolar airgap 28 may be adjusted, for example, at the base (or lowest) speed, or full-field excitation, so as to require a total interpolar excitation of 2200 ampere-turns at full load, which may be made up by 2000 ampere-turns supplied by the series commutating winding 12, and 200 cumulative ampere-turns supplied by the auxiliary commutating winding 13 of Fig. 1. Then at two times full load, still at base speed, the total interpolar excitation will be $2 \times 2000 + 200 = 4200$ ampere-turns, which is 200 ampere-turns short of the ideal double-load interpolar excitation which would be $2 \times 2200 = 4400$ ampere-turns. This has the effect of shunting out 200 ampere-turns from the commutating pole at double load, and in the case of a motor, this effect is very beneficial in producing under-compensation at overloads, thus dropping the speed-characteristic at overloads, and overcoming the tendency for the speed to rise when the motor

is overloaded. This is quite a desirable characteristic.

It is important to observe that the amount of auxiliary-winding commutating-excitation shall be within the tolerable range during which commutation shall be satisfactory, both at no load and at full load. In fact, my whole invention is possible because of the fact that these motors do not, in general, have just one exact value of interpolar excitation which is necessary to produce satisfactory commutation at any given load, but there is a certain small range of commutating values which are quite acceptable, thus enabling me to produce the effect of the old load-responsive commutating-winding shunts, by using an auxiliary commutating winding 13 having an excitation which is largely independent of the load.

It will be apparent, from the foregoing, that I have overcome the disadvantages of the previously needed heavy-current commutating-winding shunts, by the use of auxiliary multi-turn commutating-windings which carry much smaller currents, and which interpose no problem in securing the necessary adjustments. I wish it to be understood that my invention is not limited to the precise illustrations given.

I claim as my invention:

1. A variable-speed direct-current motor including an armature, a shunt-type field-winding, a shunt-field excitation-circuit including means for varying the excitation of said shunt-type field-winding over a considerable range, a series compensating winding, a series commutating winding, an auxiliary commutating winding, means for energizing the auxiliary commutating winding from the excitation-circuit of the shunt-type field-winding, the excitation of the auxiliary commutating winding being cumulative with respect to the excitation of the series commutating winding, and a ratio-adjustment means whereby to initially adjust the ratio

of responsiveness of the excitation of the auxiliary commutating winding in dependence upon the excitation of the shunt-type field-winding, said motor having adjustable-gap interpoles which carry the two commutating windings, said adjustable-gap interpoles having a gap-adjustment means whereby to initially adjust the effective interpolar airgap.

2. The invention as defined in claim 1, characterized by said ratio-adjustment means having such an adjustment that the degree of variation in the interpolar excitation under different excitations of the shunt-type field-winding is substantially as required for good commutation at a predetermined load-condition approximating a load at least as large as full load, while the excitation of the auxiliary commutating winding is within sparking-tolerable limits at no load, and further characterized by said gap-adjustment means having such an adjustment that the effective interpolar airgap makes the interpolar flux approximate an ideal good-commutation value at said predetermined load-condition at a maximum excitation of said shunt-type field-winding.

MAURICE J. PASCULLE.
